Inventor:

Peter L. Ferm,

By *George W. Ward*,
Attorney.

Patented June 19, 1923.

UNITED STATES PATENT OFFICE.

PETER L. FERM, OF KANSAS CITY, MISSOURI.

FOUNTAIN BRUSH.

Application filed January 3, 1921. Serial No. 434,431.

To all whom it may concern:

Be it known that I, PETER L. FERM, citizen of the United States, and resident of Kansas City, county of Jackson, State of Missouri, have invented a certain new and useful Improvement in Fountain Brushes, of which the following is a complete specification.

This invention relates to fountain hair brushes, and more particularly to devices of this character to be used for applying a hair tonic or oil to the scalp. My object is to produce a fountain brush which is adapted to be easily and quickly filled, and provided with a manually controlled air passage for regulating the gravitational feed of the liquid to the scalp.

A still further object is to produce a device of this character which may be readily and easily cleaned, and from which there will be no possibility of leakage when the device is not in use.

With these objects in view the invention consists in certain novel and peculiar features of construction and organization of parts as hereinafter described and claimed; and in order that it may be fully understood, reference is to be had to the accompanying drawing, in which:—

Figure 1 is a plan view of the bottom of the brush.

Figure 2 is a section on the line II—II of Figure 1.

Figure 3 is a fragmental section of the brush and illustrates another form of air passage.

In the said drawing, where like reference characters identify corresponding parts in all of the figures, 1 is a container, preferably of circular form for convenience in being gripped by the hand of the operator, and provided with a concave bottom portion 2, equipped with a screw cap 3, which will form a liquid-tight closure for the threaded filling opening 15 formed in the bottom 2, the shape of the latter being such that the liquid may readily and easily be poured into the container. The container 2 is provided with an enlarged portion 4, forming an air passage 5, said passage being equipped at its outer end with a cup shaped opening 6 for convenient closure by the finger of the operator, as hereinafter described.

The bottom of the container is provided with a circumferential series of teeth 7 of semi-flexible material, formed with passages

8 communicating with the interior of the container 2, and through which the liquid in the latter is adapted to escape.

In the form of the brush illustrated by Figure 3, a perforation 9 is made at a convenient point in the top of the container, and a pair of ears 10 are formed on the exterior side wall thereof at a point near the perforation 9, and below said ears is a pin 11. Pivoted between the ears is a lever 12 formed at its upper end with a right-angle portion 13 adapted for closing the perforation in the top under the pressure of a spring 14, fitting between the lower finger portion of the lever and the container, and held in position by the pin 11. With this form of air passage, the operation of the brush is similar in all respects to the operation of the form of brush having the passage 5, except that the spring-actuated lever will close the air passage automatically when the finger of the operator ceases to exert pressure to hold such passage open, and it will, therefore, be unnecessary for the operator to continuously maintain his finger on the opening of the air passage in order to prevent the escape of liquid from the teeth of the brush.

The operation of the brush is as follows: When it is desired to fill the container, the brush is placed bottom side up, and the screw cap 3 is removed and liquid is poured into the container, the concave form of bottom facilitating the filling operation and lessening the tendency of the liquid to slop over the sides of the container; it will also be noted that the depth of the concave bottom 2, is such that no liquid can escape through the air passage 5, but will overflow through the filling opening 15. After the desired quantity of liquid has been poured into the container, the screw cap is placed in position and forms a liquid tight joint with the bottom 2. The brush is now ready for use, the liquid standing therein to a point substantially as shown in Figure 2. The operator will place his finger over the cup-shaped opening 6 and invert the brush, the liquid being held in the container by air pressure. The operator will then rub the brush over the scalp of the patient, removing his finger from opening 6 of the air passage 5 from time to time, in order to permit air to enter the container and cause the liquid to be discharged through the teeth of the brush under gravitational action.

This operation will be repeated as a further quantity of the liquid is found necessary. With the modification shown in Figure 3, the operator will simply manipulate the lever 12 to regulate the feed of the liquid in an obvious manner.

From the above description it will be apparent that I have produced a fountain brush of the character set forth, which possesses all the features of advantage enumerated as desirable, and while I have described and claimed the preferred embodiment of the same, I reserve the right to make all changes properly falling within the spirit and scope of the appended claims.

I claim:

1. In a device of the character described, a liquid container provided with top and bottom portions and formed with an air passage in its side wall having its opposite ends respectively in proximity to the bottom and top portions of the container, and with its exit opening in convenient position for operation by the operator, the bottom portion being provided with a filling opening, and a series of teeth internally formed with exit openings in communication with the container.

2. In a device of the character described, a liquid container provided with an enlarged portion in its side wall having an air passage communicating with the container above the surface of the liquid therein, said passage being formed with a cup-shaped mouth, said mouth being in convenient position for operation by the operator, a bottom for the container provided with a filling opening, and a series of teeth provided with liquid exit passages communicating with said container.

3. In a device of the character described, a liquid container formed with a concave bottom provided with a filling opening, said container also having an air passage formed in its side wall and in communication with said container above the surface of the liquid therein and having its inner end in a horizontal plane above that of the filling opening and having its exterior mouth in a plane below that of the filling opening, said mouth being in convenient position for operation by the operator, and a series of hollow teeth in communication with said container.

In witness whereof I affix my signature.

PETER L. FERM.
